ELECTRICAL POCKET WRITING AND READING LAMP

Franz Kostal, Vienna, Austria, assignor to Wilhelm Ernst Reeser, Modling-Hinterbruhl, Austria

Application October 26, 1937, Serial No. 171,047
In Austria January 25, 1937

3 Claims. (Cl. 240—6.4)

My invention has for its object to provide an adjustable battery lamp, which in its closed position may be carried in the pocket and which, in its open position, provides an excellent illumination of the writing or reading surface of a writing pad or book, on which it may be easily attached. The lamp according to the invention allows to read and write in the darkness and is therefore particularly adapted for military and 10 police use.

With this main object in view my lamp comprises a tubular casing, containing a battery of dry cells and to which is movably connected a hollow arm rotatably mounted on one end of said 15 casing and bearing on its free end a receptacle for a flashlight lamp. The casing may be provided with means for clamping the whole structure for instance to the edge of a book or pad. The swivel joint between the casing and said 20 arm is arranged to form a contact means for transmitting the current to said lamp-receptacle during the rotation of the arm. In a preferred embodiment of the invention, however, the said contact means are arranged to form a switch 25 which shuts off the current in the closed position of the lamp, so that the same cannot be lighted accidentally while carried in the pocket in its closed position.

The invention is illustrated by way of example 30 in the accompanying drawing, in which Fig. 1 is a section along the axis of the device in its closed position, Fig. 1a a fragmentary section of the upper part of the battery casing along the axis at right angle to the section of Fig. 1; Fig. 2 shows the device in a perspective view in its open 35 or operative position, Fig. 3 is a plan view of another embodiment of the device and Fig. 4 shows in perspective view the lamp according to Fig. 3 in use and clamped to a writing pad in its open 40 position.

With reference to the drawing, 1 is a tubular casing made for instance of metal and closed at one end by a cap 2 and at the other end by a screw-cap 3 bearing a coil-spring 4. Dry cells 45 5 and 6 are arranged in axial alignment in a shell 1 of cardboard and inserted into the casing 1 where they are pressed towards the upper end (Fig. 1) by the spring 4. A hollow metal arm 8 of substantially U-shape is rotatably mounted in the upper end of the casing 1, one of the legs of the U being perpendicular to the axis of said casing and journalled in openings of the walls of the same. Said openings may be open slots 50 closed by the lower edge of cap 2, so that the leg

of the arm 9 may be easily mounted and removed.

A hollow drum 10 of insulating material is mounted on said leg of the arm 8 and bears a contact ring 11 to which the conductor of an insulated wire 9 is soldered or otherwise connected. Said wire is enclosed within the hollow arm 8 and passes through an opening or slot in said arm and another slot in the drum 10. One contact, for instance the positive contact 6a of the dry cell 6 is pressed by the spring 4 against the ring 11.

To the other end of the arm 8 a tubular lamp casing 12 made of metal is rigidly attached or movably hinged. Said casing contains a washer 13 of insulating material having a central contact screw or rivet 14 to which the conductor of the insulated wire 9 is soldered or otherwise attached. A reflector 15 is screwed or otherwise fixed to the lamp casing 12 and forms a receptacle for a 20 flashlight lamp 16, the tip of said lamp making contact with the screw 14.

On the casing 1 means are attached to clamp the same to the edge of a book or writing pad. Said means may comprise a wing 17 of thin spring 25 sheet metal soldered to the casing 1, two U-shaped slots forming two resilient tabs 18, so that the book or pad 20 or a part thereof may be clamped between said tabs 18 and the wing 17, as shown in Fig. 4.

In operation, the arm 8 is swung to the position shown in Fig. 2. The current passes from the positive contact 6a of the dry cell 6 to the ring 11 and through the conductor of the insulated wire 9 and screw 14 to the tip contact of the 35 lamp 16. The shell contact of said lamp is connected through the metal casing 12, arm 8 to the casing 1 and by means of the spring 4 to the negative contact of dry cell 5. The dry cells 5 and 6 are connected in series, as usual and as 40 shown in Fig. 1.

Switching may be effected by turning the screw cap 3 and thus tightening and loosening the spring 4. In the embodiment shown in Fig. 1a, a sector of the ring 11 is cut away and replaced 45 by insulated material 10a. The drum 10 is so positioned on the leg of the arm 8 that in the closed position of the device, the contact 6a rests upon the insulating piece 10a as shown by Fig. 1a, the current being interrupted in this position. 50 If the arm 8 is swung into its operative position, the contact 6a slides upon the ring 11 and contact is automatically established.

In the modification shown in Figs. 3 and 4 the whole arm or a part of the arm 8 is formed by a 55

flexible metal tubing 8a, so that the lamp casing 12 with the lamp 16 may be brought to the most convenient position for writing or reading. Instead of said flexible tubing flexible joints or a ball joint may be inserted into the arm.

5 What I claim is:

1. In a device of the class described, a tubular casing, a wing projecting from said casing and having tabs adapted to clamp a book or pad, a tubular arm bearing on one end a lamp receptacle and having a leg bent at a right angle on its other end, said leg being rotatably mounted at one end of said casing, a drum of insulating material upon said leg within said casing, a contact ring upon said drum, a battery enclosed within said casing, a spring urging said battery towards said contact ring, and an insulated wire concealed within said tubular arm, the conductor of said wire being connected to said contact ring and to the tip contact of said receptacle.
- 10 2. In a device of the class described, a tubular casing, a wing projecting from said casing and having tabs adapted to clamp a book or pad, a tubular arm bearing on one end a lamp receptacle
- 15
- 20

and having a leg bent at a right angle on its other end, said leg being rotatably mounted at one end of said casing, a drum of insulating material upon said leg within said casing, a contact ring upon said drum, a segment of said ring being cut away, a battery enclosed within said casing, a spring urging said battery towards said contact ring, and an insulated wire concealed within said tubular arm, the conductor of said wire being connected to said contact ring and to the tip contact of said receptacle.

5

3. In a device of the class described, a tubular casing provided with means for clamping the object to be illuminated, said casing being adapted to enclose a battery, a straight, hollow arm of greater length than said casing and pivotally connected with one of its ends to one end of said casing, a tubular receptacle attached to the other end of said arm, capable of being brought into alignment with the battery casing, in one position, and conducting means within said hollow arm to transmit current from a battery within the casing to the said lamp receptacle.

FRANZ KOSTAL.
